TIME DELAY SWITCH

Leopold Uriag, Berlin, Germany

Application March 18, 1936, Serial No. 69,467
In Germany June 6, 1934

7 Claims. (CL 200—33)

The invention relates to improvements in time-delay switches, meaning such switches in which the circuit connection is effected by hand and which disconnect the circuit automatically after the lapse of a certain interval of time. In order to regulate the time of delay mechanical clock-works or pneumatic pistons or bellows have been applied, whereby particularly complicated devices were required for performing the instantaneous interruption as is imperative for disconnecting electrical switches. The present invention makes use of a suction-cup which—under the influence of a counter-spring—will jump off instantaneously and automatically as soon as the sucking effect has become insufficient, and the invention also provides devices for enabling one to predetermine exactly the time-interval of the connection.

Another object of the invention is to regulate or fix the delay-time by means of an air-channel leading to the hollow space which is formed by the suction-cup and its counter-plate, when either of these is pressed against the other for the purpose of completing the circuit by closing the contact. Through this air-channel the hollow space fills slowly with air within the predetermined time, whereupon the suction-cup will jump off and break the circuit. The channel has adjustable devices for throttling in order to be able to regulate the time-interval for the influx of air.

A further object of the invention is to ensure the suction effect by providing a projecting ring on the counter-plate, upon which the overlapping rim of the suction-cup is pressed down, thus forming an entirely tight closure of the hollow space between suction-cup and counter-plate. The channel leading into the hollow space, or the edge between the ring and the suction-cup can possess a minute opening of unadjustable or definite width, and the regulation of the time-delay may then be effected by providing the movable part with adjustable touching projections destined to limit the depth to which the suction-cup can be pressed against its counter-plate or vice-versa.

A further object of the invention is to obtain instantaneous circuit-completion under all conditions by means of a hinged contact plate which is connected to the movable contact member by means of elastic links or springs. This contact member is brought from the open to the closed position instantaneously as soon as the force of the elastic connection surpasses the force of means provided for retaining the contact plate in

its open position. In this manner both the completing as well as the breaking of the circuit will be effected instantaneously, even if the pressure brought upon the contact member is exerted slowly.

5 Further details of the invention are described hereinafter and illustrated by the accompanying drawings, which show different kinds of switches according to the invention.

10 In the drawings is:

Fig. 1 is a vertical section through the switch in the direction 1—1 of Fig. 3.

Fig. 2 is a view from above upon the lower part of the switch,

15 Fig. 3 a view from above upon the switch,

Fig. 4 a vertical section through a different form of executing the switch,

Fig. 5 a vertical section in part, through another form of executing the switch,

20 Fig. 6 a vertical section through a further form of executing the switch in open position,

Fig. 7 a view from above upon the switch of Fig. 6, in part section, when the covering cap is removed,

25 Fig. 8 is a vertical section through the switch of Fig. 7 in closed position,

Fig. 9 is a further modified form of execution, in part section, in closed position,

Fig. 10 a further modified form of execution, in part section, in open position.

30 In all the drawings identical parts are marked with identical numbers.

In the example according to Figs. 1—3 the switch consists of a bottom-plate 1 forming the counter-plate for the suction-cup 2 and being provided with the projecting ring 3. The suction-cup 2 is fixed to the socket 4 which is lodged movably in the opening 5 of the covering cap 6. In the socket 4 there is fixed a disk 7 to which 35 is fastened the screw-bolt 8 of the push-button 9. A spring 10 surrounds the socket 4 which is prevented from twisting by a longitudinal slot 11. The suction-cup 2 is clasped by a contact spring 12 fastened to the cap 6 by means of the screw 13 and whose front end bearing the contact-plate 14 is capable of creating a connection between the contacts 15 and 16. The suction-cup 2 is penetrated by an air-channel 17 which is closed from above by a plate 18 pressed by the screw 8. Between the suction-cup 2 and the plate 18 there is inserted a thread 19. A detent-lever 21 is loosely held by the screw 20 on the bottom-plate 1. A ratchet-lever 22 is fixed movably at the point 23 of the cap 6 and can be in-

serted into a slot 24 of the opening 5 when the button 9 has been pressed down.

The device is acting as follows:

By exerting a pressure upon the button 9 the switch can be pushed down into the closed position shown in broken lines. In this position the suction-cup 2 covers the ring 4 and is retained there by the effect of the suction. The contact-plate 14 will then connect the contacts 15 and 16 with each other. Air is slowly entering 10 through the channel 17 into the hollow space between the cup 2 and the counter-plate 1, until the suction-effect of the cup becomes inferior to the force of the tension-spring 10. In this moment the suction-cup jumps off and the circuit is 15 broken abruptly.

The volume of the entering air-current and consequently the time-interval of the delay can be regulated by means of the screw 8 which presses the plate 18 more or less tightly against the mouth of channel 17. The thread 19 has the effect that this opening can never be closed completely. If the switch is intended to keep the circuit permanently closed the button 9 is pressed down and the lever 22 then pushed home, so that it blocks the backward movement of the button. If on the other hand a breaking of the circuit is required before the lapse of the delay-time, the lever 21 is pressed thereby lifting up the edge of the suction-cup 2 from the projection 3, thus allowing much air to enter into the hollow space and causing the suction-cup to jump off immediately.

In the example according to Fig. 4 the suction-cup 2 is permanently screwed on the bottom-plate 1 by means of a bolt 25, a spacing or distance-collar 26 and the nut 27. The inner part of the push-button 28 forms the counter-plate and is provided with the projection 3 to which the suction-cup 2 attaches itself by suction as soon as the button 28 is pushed down against the tension of the spring 29. The circuit between the contacts 15 and 16 is closed by the contact pieces 30. The air enters into the hollow space of the suction-cup through the chinks between the bolt 25 and the tube 26; the size of the opening can be adjusted by the screw 31.

In the example according to Fig. 5 the air-channel 32 is provided in the movable counter-plate 33 and is closed by an India-rubber plate 34. The latter is arranged within a filtering 35, e. g. made of felt, and is pressed against the opening 32 by a forcing lever 36 which is held on one side by a nut with counter-nut and bolt 37 and on the other side on the bolt 39 by an adjustable screw 38 provided with an index-finger. Below the screw 38 there is a dial 40. The room for the adjusting device is closed at the top by a covering lid 41 which can be screwed on. After having once correctly adjusted the nuts 37, this arrangement will allow by twisting the index-finger screw 38 above the dial 40 to determine as delay-time that interval of time, which can be read off the dial 40.

In the switch according to Figs. 6-8 the suction-cup 2 is not connected immediately to the contact member. In this case the contact member consists of the plate 42 hinged movably at the axle 44 and bearing at its front end the surface 43 closing the circuit between the contacts 15 and 16. The axle 44 is fixed to the bridge 53 which holds also the suction-cup 2. The push-button 45 is screwed into the socket 4 bearing the suction-cup 2, with its lower end 46 being

provided with a worm. One arm 47 of a spring, the other end of which is connected to the plate 42 by means of the branches 48, gears into the lower part of the socket 4. An arresting spring 49 retains the plate 42 in open position. The 5 detent-lever 21 is held by the spring 50 which is supported by the axle 44.

The switch according to Figs. 6-8 acts as follows:

When the button 44 is pushed down together with the suction-cup 2, the spring 49 will first hold the plate 42 in the open position. Only when the suction-cup 2 is firmly attached to counter-plate 1, the force of the sole spring 47 is sufficiently large to overcome the force of the arresting spring 49. The plate 42 will then assume abruptly the closed position as shown in Fig. 8. When, after the influx of air into the hollow space, the suction-cup under the influence of the counter-spring 10 is jumping off suddenly, the plate 42 all of a sudden will turn just as abruptly into the open position of Fig. 6 and the circuit is broken.

The adjustment of the length of time for the 25 delay is performed by twisting the push-button 45 whereby the plate 18 is pressed more or less tightly against the mouth of the air-channel 17. The socket 4 is guarded against twisting, as may be seen from Fig. 7, by its lower part 51 being 30 formed quadrangularly and placed in a gap 52 of the plate 42.

In the example of Fig. 9 the bridge has a 35 socket-like upper extension 54, the end of which forms touching surfaces for the push-button 45. With this arrangement it is possible to vary the depth to which the socket 4 together with the suction-cup 2 can be pressed down, by twisting the knob 45

Through an adjustable or definite leak, e. g. 40 a minute rift or fissure in the projection 3, air is entering into the hollow space and allows the suction-cup 2 to jump off within a certain time which is shorter, the less deep the cup had been pressed down upon the counter-plate 1.

In the example according to Fig. 10 a pin 55 serves as a touching part limiting the downward movement of the suction-cup 2. The depth is 45 adjustable by turning the screw 56 which can only be adjusted after removing the push-button 50 45.

What I claim is:

1. In a switch of the class described, the combination of a casing, a terminal support arranged in said casing, a plurality of circuit terminals carried by said support, a control member movably arranged in an opening of said casing, a bridging contact connected to said control member and adapted to be moved into engagement with said circuit terminals, retarding means for maintaining the bridging contact in engagement with the circuit terminals during a predetermined period of time, said retarding means comprising a suction-cup member and a counter-plate member, one of said members being connected to said control member the other one being connected to said support, said control member being depressible to move said bridging contact into engagement with said circuit terminals and to engage the members of 60 said retarding means with each other thereby forming a hollow chamber within said members, a channel passing through the wall of the suction-cup member and communicating said hollow chamber through said opening of the casing 65 with the air outside of the latter, a valve plate 70 75

adapted to be moved against the open end of said channel to determine the amount of air flowing into said hollow space, a screw connected to said control member, said screw cooperating with said valve plate and being rotatable by a rotation of said control member to move said valve plate relatively to said open end of the channel, and a resilient member acting on said retarding means to instantaneously disengage the members thereof from each other after a predetermined pressure of the air in said hollow chamber has been reached.

2. In a switch of the class described, the combination of a casing, a terminal support arranged in said casing, a plurality of circuit terminals carried by said support, a control member movably arranged in an opening of said casing, a bridging contact connected to said control member and adapted to be moved into engagement with said circuit terminals, retarding means for maintaining the bridging contact in engagement with the circuit terminals during a predetermined period of time, said retarding means comprising a suction-cup member and a counter-plate member, one of said members being connected to said control member the other one being connected to said support, said control member being compressible to move said bridging contact into engagement with said circuit terminals and to engage the members of said retarding means with each other thereby forming a hollow chamber within said members, a channel passing through the wall of the suction-cup member and communicating said hollow chamber through said opening of the casing with the air outside of the latter, a thread arranged over the open end of said channel to establish a constant leakage, a valve plate adapted to be moved against said thread and the open end of said channel to determine the amount of air flowing into said hollow space, a screw connected to said control member, said screw cooperating with said valve plate and being rotatable by a rotation of said control member to move said valve plate relatively to said open end of the channel, and a resilient member acting on said retarding means to instantaneously disengage the members thereof from each other after a predetermined pressure of the air in said hollow chamber has been reached.

3. In a switch of the class described, the combination of a casing, a terminal support arranged in said casing, a plurality of circuit terminals carried by said support, a control member movably arranged in an opening of said casing, a bridging contact connected to said control member and adapted to be moved into engagement with said circuit terminals, retarding means for maintaining the bridging contact in engagement with the circuit terminals during a predetermined period of time, said retarding means comprising a suction-cup member and a counter-plate member, one of said members being connected to said control member, the other one being connected to said support, said control member being compressible to move said bridging contact into engagement with said circuit terminals and to engage the members of said retarding means with each other thereby forming a hollow chamber within said members, a channel communicating said hollow chamber with the air outside of the casing, an adjustable stop arranged in said casing to limit the relative movement of the members of the retarding means against each other, and a resilient member acting on said re-

tarding means to instantaneously disengage the members thereof from each other after a predetermined pressure of the air in said hollow chamber has been reached.

5. In a switch of the class described, the combination of a casing, a terminal support arranged in said casing, a plurality of circuit terminals carried by said support, a control member movably arranged in an opening of said casing, a bridging contact connected to said control member and adapted to be moved into engagement with said circuit terminals, retarding means for maintaining the bridging contact in engagement with the circuit terminals during a predetermined period of time, said retarding means comprising a suction-cup member and a counter-plate member provided with a projecting rim adapted to engage along its outer circumference with the inside of the suction-cup member, one of said members being connected to said control member the other one being connected to said support, said control member being compressible to move said bridging contact into engagement with said circuit terminals and to engage the members of said retarding means with each other thereby forming a hollow chamber within said members, a channel communicating said hollow chamber with the air outside of the casing, an adjustable stop arranged in said casing to limit the relative movement of the members of the retarding means against each other, and a resilient member acting on said retarding means to instantaneously disengage the members thereof from each other after a predetermined pressure of the air in said hollow chamber has been reached.

5. In a switch of the class described, the combination of a casing, a terminal support arranged in said casing, a plurality of circuit terminals carried by said support, a control member movably arranged in an opening of said casing, a bridging contact adapted to be moved into engagement with said circuit terminals, resilient means connecting said bridging contact to said control member, retarding means for maintaining the bridging contact in engagement with the circuit terminals during a predetermined period of time, said retarding means comprising a suction-cup member and a counter-plate member, one of said members being connected to said control member the other one being connected to said support, said control member being compressible to move said bridging contact after overcoming the force of said resilient connecting means into engagement with said circuit terminals and to engage the members of said retarding means with each other thereby forming a hollow chamber within said members, a channel communicating said hollow chamber with the air outside of the casing, throttling means arranged in said channel to determine the amount of air flowing into said hollow chamber and a resilient member acting on said retarding means to instantaneously disengage the members thereof from each other after a predetermined pressure of the air in said hollow chamber has been reached.

6. In a switch of the class described, the combination of a casing, a terminal support arranged in said casing, a plurality of circuit terminals carried by said support, a control member movably arranged in an opening of said casing, a bridging contact connected to said control member and adapted to be moved into engagement with said circuit terminals, retarding means for maintaining the bridging contact in engagement

with the circuit terminals during a predetermined period of time, said retarding means comprising a suction-cup member and a counter-plate member provided with a projecting rim adapted to engage along its outer circumference with the inside of the suction-cup member, one of said members being connected to said control member the other one being connected to said support, said control member being depressible to move said bridging contact into engagement with said circuit terminals and to engage the members of said retarding means with each other thereby forming a hollow chamber within said members, a lever movably arranged on said support, one end of which projecting through an opening of the casing the other end of which extending below the edge of the suction-cup member and being adapted to raise same, and a resilient member acting on said retarding means to instantaneously disengage the members thereof from each other after a predetermined pressure of the air in said hollow chamber has been reached.

7. In a switch of the class described, the combination of a casing, a terminal support arranged in said casing, a plurality of circuit terminals carried by said support, a control member movably arranged in an opening of said casing, a bridging contact connected to said control member and adapted to be moved into engagement

with said circuit terminals, retarding means for maintaining the bridging contact in engagement with the circuit terminals during a predetermined period of time, said retarding means comprising a suction-cup member and a counter-plate member provided with a projecting rim adapted to engage along its outer circumference with the inside of the suction-cup member, one of said members being connected to said control member the other one being connected to said support, said control member being depressible to move said bridging contact into engagement with said circuit terminals and to engage the members of said retarding means with each other thereby forming a hollow chamber within said members, a channel communicating said hollow chamber with the air outside of the casing, throttling means arranged in said channel to determine the amount of air flowing into said hollow chamber, a lever movably arranged on said support, one end of which projecting through an opening of the casing the other end of which extending below the edge of the suction-cup member and being adapted to raise same, and a resilient member acting on said retarding means to instantaneously disengage the members thereof from each other after a predetermined pressure of the air in said hollow chamber has been reached.

LEOPOLD URIGA.
